UNITED STATES PATENT OFFICE.

RICHARD HANS GÄRTNER, OF HAMBURG, GERMANY.

METHOD FOR REMOVING TETRANITROMETHANE FROM TRINITROTOLUENE.

Application filed December 18, 1924, Serial No. 756,830, and in Germany December 31, 1923.

Technical trinitrotoluene, which as is well known is produced by nitrating nitrotoluene, contains impurities which diminish its stability and are prejudicial to its further treatment and even to its use particularly from a sanitary point of view. These impurities are formed mainly by isomeric trinitrotoluenes, bi-nitrotoluene and tetranitromethane. They can, it is true, be removed by recrystallization but this is a very tedious and somewhat expensive process, and moreover involves dealing with the mother liquor which is dangerous and unhygienic.

The formation of isomeric trinitrotoluenes and the bi-nitrotoluene can be avoided if nitrotoluene or bi-nitrotoluene free from metanitrotoluene and free from meta-bi-nitrotoluene is further nitrated. But when nitrating it is impossible to prevent the formation of tetranitromethane which therefore still remains and must be subsequently removed. It has been proposed to blow off the tetranitromethane from the trinitrotoluene by steam or by air but this process requires a very large amount of steam and also takes considerable time. Moreover the trinitrotoluene, if this process is adopted assumes a dark colour which is not what is wanted.

The object of the present invention is to discover a method which enables the tetranitromethane to be completely removed from the technical trinitrotoluene without impairing the latter and at the same time obtaining a stable product. The method consists in the atomization of technical trinitrotoluene by a stream of hot air directed from nozzles or similar devices in a manner known per se, and in then freeing it from the tetranitromethane by further streams of air heated to suitable temperatures and finally allowing it to solidify. This effect will take place in a very short time and with a very small consumption of hot air.

The clouds and small drops produced in atomizing by hot air have a large superficial area and since they solidify slowly the tetranitromethane quickly evaporates. In the upper part of the drying chamber, where are situated the nozzles or similar devices for atomizing, in addition to the stream of hot air employed for the atomization another stream of hot air is employed to keep the trinitrotoluene drops in a liquid state for a longer period. In the lower part of the chamber the trinitrotoluene will be cooled

down by a stream of cold air and thus solidified. Generally one treatment will be sufficient to deprive the trinitrotoluene completely of the tetranitromethane but the process can be repeated if desirable after the trinitrotoluene has been melted again in any known manner.

Reference may now be made to the accompanying drawing in which is illustrated a suitable apparatus for carrying out the method described above.

The trinitrotoluene is melted in a vessel *a*, from the lower end of which leads the pipe *b* terminating in an atomizing nozzle *c* in a known manner within the operating tank *d*. Air heated by a calorifier *e* is forced by a fan *f* through the pipe *g* into the tank *d* opposite the atomizer *c*, the tetranitromethane being separated from the trinitrotoluene by this stream of hot air and the trinitrotoluene atomized thereby. The clouds and small particles produced by the atomizing nozzle will move downwards within the tank *d*, and are kept in a liquid state by another stream of hot air admitted through the pipe *o* from any convenient source. In the lower part *d'* of the tank *d* a cold stream of air forced into the tank by the fan *f'* cools down the trinitrotoluene. Both the hot air or gases from the top and the cold air from below will be drawn away by the intermediate pipe *h*, which is preferably not connected directly to the fan *f'*, that communicates directly with the atmosphere through the long vertical pipe *i*, but through the intermediary of a settling tank *k* into the bottom of which the pipe *h* projects while the connecting pipe *m* of the fan *f'* branches off from the top of the tank *k*. This tank serves to absorb the tetranitromethane and also any trinitrotoluene that remains in the gases drawn off by the fan *f'*.

As described above in the upper part of the tank *d* the trinitrotoluene particles are kept for a considerable time in a liquid state by the hot stream of air introduced by the pipe *o*. The cold air introduced by the fan *f'* cools the trinitrotoluene to such an extent that it is solidified. The solidified trinitrotoluene will be collected in the funnel shaped bottom *n* of the tank *d* from the exit of which the trinitrotoluene is gathered in a powdered state.

It may be remarked that it is known to dry trinitrotoluene by causing it to flow in a liquid state over a heated open tray for a

sufficient period of time. This process effects drying in a continuous operation, while at the same time exposes only a small quantity at a time to the action of heat and 5 only for a short time. Apart from the fact that it seems very doubtful whether the trinitrotoluene can be freed by this method from the tetrinitromethane it has the disadvantage supposing it to be used for the 10 purpose which is here in question, that the insanitary tetrinitromethane will escape into the air of the workroom and that very large mechanical plants would be required. Both these drawbacks are absent from the 15 method proposed by this invention.

This method can be further improved upon by using steam or any other gaseous stream at a suitable pressure for atomizing the trinitrotoluene instead of a stream of 20 hot air. The use of steam has the advantages that the tetrinitromethane will be more easily removed, that the velocity of the stream of steam can be regulated by changing the pressure and that the constituents 25 evaporated by the steam can be recovered more easily than substances evaporated by air.

As previously described when hot air is employed for the atomization the atomized 30 trinitrotoluene is kept in a liquid state by another stream of hot air so in a like manner when steam is employed the atomization within the upper part of the chamber is caused by steam and the atomized trinitrotoluene is first kept in a liquid state either by hot air or by steam, and finally is caused 35

to solidify in the lower part of the chamber by a stream of cold air.

The trinitrotoluene thus produced retains its natural light colour and is free from all 40 foreign constituents that are decomposable or are noxious to the health of the workmen.

Having now particularly described and ascertained the nature of my said invention 45 and in what manner the same is to be performed, I declare that what I claim is:—

1. A method for removing tetrinitromethane from commercial trinitrotoluene comprising, atomizing commercial liquid trinitrotoluene by means of a nonreactive hot gaseous stream, subjecting the clouds thus produced to hot nonreactive gaseous streams until the tetrinitromethane is vaporized, then subjecting the trinitrotoluene to cold 50 non-reactive gaseous streams by which the trinitrotoluene is solidified, and then withdrawing the hot gases from the presence of the solidified trinitrotoluene.

2. A method for removing tetrinitromethane from commercial trinitrotoluene comprising, atomizing liquid commercial trinitrotoluene by means of a stream of hot air, subjecting the clouds thus produced to streams of hot air until the tetrinitromethane is vaporized, subjecting the trinitrotoluene to streams of cold air by which the trinitrotoluene is solidified, and withdrawing the hot air from the presence of solidified trinitrotoluene.

RICHARD HANS GÄRTNER.
